UNITED STATES PATENT OFFICE.

CHRISTIAN SCHNEIDER, OF SHEFFIELD, ENGLAND.

ATTACHMENT TO BOILER AND OTHER FURNACES.

1,190,331.

Specification of Letters Patent.

Patented July 11, 1916.

Application filed March 9, 1914. Serial No. 823,631.

To all whom it may concern:

Be it known that I, CHRISTIAN SCHNEIDER, of the city of Sheffield, in the county of Yorkshire, England, have invented certain new and useful Improvements in Attachments to Boiler and other Furnaces, of which the following is the specification.

The invention relates to attachments to boiler and other furnaces and the object of 10 the invention is to provide a simple and efficient device for supplying air to the combustion chamber of boiler furnaces for the purpose of consuming smoke within the furnace, the device when installed providing 15 for the quicker generation of steam than can be done in ordinary circumstances also for effecting the extracting and consumption of the combustible gases and as far as possible the carbon or coke where coal is used as a 20 fuel, this latter feature effecting economy in fuel.

With the above objects in view the invention consists essentially in means for admitting a steam jet into the furnace from 25 the front and above the grates and means for admitting a forced air draft to the furnace at the back from beneath the grates, the jet and air draft so provided effecting a baffling of the smoke in the furnace 30 and the consequent consumption of the combustible material in the smoke by the fire of the furnace, the parts being arranged and constructed as hereinafter more particularly described and later pointed out in the appended claim.

Figure 1 represents a front view of part of a furnace with my invention applied. Fig. 2 is a longitudinal sectional view through the furnace. Fig. 3 is an enlarged 40 detailed vertical sectional view through the furnace, the section being taken in the plane denoted by the line $x-x$ Fig. 2. Fig. 4 is a side view of the combination air box and bridge. Fig. 5 is a plan view of the air box and bridge. Fig. 6 is a vertical sectional view through the air box and bridge. Fig. 7 is an enlarged detailed vertical sectional view through one of the steam nozzles, the section being taken in the plane denoted by the line $Y-Y$ Fig. 1. Fig. 8 is an enlarged detailed sectional view through 50 the cross plate showing the controlling rod passing through the same.

In the drawings like characters of reference indicate corresponding parts in each figure.

1 represents the boiler, 1' the front end plate, 2 the furnace, 3 the flue, 4 the grate bars, 5 the ashpit, 6 the furnace end plate and 7 the furnace door, the door being hinged to the end plate at 8 as is customary.

9 is a cross plate permanently secured to the lower edge of the front plate which it will be noticed terminates at a short distance beneath the furnace door. This cross plate carries a damper 10 which controls the entrance to the ashpit, the damper being connected to the cross plate by hinges 11.

12 is a steam pipe leading from the top 73 of the boiler and provided with a T-connection from which I pass a feed pipe 14, the said feed pipe being supported in any suitable way from the cross plate and passing lengthwise of the same and being fitted with 75 a plurality of steam nozzles 15 which project into the furnace through suitable air openings 16 provided in the cross plate. Air tubes 17 surround the nozzles and are secured to the inner face of the plate, the 80 openings in the tubes being continuous with the air inlet openings 16. It is to be noticed that these nozzles and air tubes are located at the front beneath the grates. The pipe 14 is supplied with a controlling valve 18. 85

19 is a chain connected to the damper and having any one of the links thereof connected to a hook 20 carried by the cross plate. The position of the damper can be adjusted by means of the chain and hook. 90 21 is a second branch steam pipe connected to the T-piece 13 and having the lower end thereof passing through the end plate 6 directly above the door, the said end terminating in a contracted nozzle 22. 23 is a 95 strap fastening the lower end of the pipe to the end plate 6 and 21' is a controlling valve located in the pipe 21. It is to be noted that this latter nozzle is well above the grates. The forward end of the grate bars are supported in the usual way from the door frame structure while the rear ends are mounted on a special cross bar 25 which I provide. 100 26 is a second cross bar located immediately to the rear of the cross bar 25 and spaced from the same with sufficient clearance to allow for expansion and contraction. It will be understood that it is not necessary to provide a special fastening to connect these bars with the sides of the furnace as they 105 have their ends cut to correspond with the curvature of the sides of the furnace.

110

27 is a baffle wall formed from fire bricks, which baffle wall is built up in the furnace to the rear of the cross bar 26 and has the upper face thereof horizontal and directly 5 opposite the upper face of the latter bar.

28 is a combined air box and bridge having the front side thereof mounted on the bars and the rear side mounted on the baffle wall. This air box and bridge is formed in the 10 special manner now described. It comprises essentially three parts, a bed plate 29, a box like structure 30 and a damper 31.

The bed plate is supplied with a damper opening 32 which receives pivotally the 15 damper 31 and is provided further with pairs of upstanding stops or lugs 33 located to the sides of the damper opening which lugs receive between them the lower edge of the box like structure 30, there being sufficient 20 clearance to allow of expansion and contraction. The bed plate lies on the bars and baffle wall with the ends of the plate butting against the interior walls of the furnace, particular care being taken in setting 25 it so that the damper is free to operate in the open space reserved between the cross bar 26 and the wall 27. The box like structure 30 has the sides and ends thereof tapering slightly upwardly so that the opening 30 at the top is somewhat contracted. The box is somewhat shorter and narrower than the bed plate so that fire brick can be built up 35 around the box to inclose the same, the fire brick 34 resting on the bed plate. The upper or outlet end of the box extends well above the level of the grates.

The damper is provided with an extending eye bolt 35 connected to a controlling rod 36 which passes forwardly beneath the 40 grates and through a suitable opening formed in the cross plate 9.

The forward end of the bar is provided with a handle and is fitted also at the lower edge with teeth 37 whereby the rod and 45 consequently the damper can be adjusted, the teeth being arranged to engage with the side of the opening in the plate.

When the device is used steam is turned on by opening the valves 18 and 24. The 50 steam issuing through the nozzles 15 causes a forced air draft beneath the grates the air entering through the air tubes 17. Part of this air passes through the grates and supports combustion, while some of it passes 55 rearwardly to the box and through the same to the back of the furnace, the supply through the box being controlled by the damper, which can be set by the attendant as required by manipulating the rod. The 60 steam admitted above the fire through the jet 22 operates to baffle the smoke rising from the fire. In actual practice this jet is directed to the upper edge of the air box.

The products of combustion, by the combined effect of the top steam jet above the 65 fire and the air draft through the air box at the back of the fire, are baffled and retained above the fire with the result that the combustible material is burned before escaping to the flue over the air box. Sufficient oxygen 70 is supplied by the top steam jet and by the air admitted at the back to insure complete combustion of the combustible material.

It will be seen that the wall 27 forms not 75 only a support for the box but also prevents any air entering the flue except by way of the air box.

I might here mention that in boilers with a small furnace and in those that are worked 80 at low pressure it is unnecessary to supply the air box as the nozzle 22 in combination with the nozzles 15 and air tubes 17 will supply sufficient air to consume all the smoke rising from the fire, the jet 22 acting to baffle down the smoke rising from the fire and retaining it in close proximity to the flame of the fire until it is consumed. However in steam boilers with large furnaces and in those that are worked at high pressure I 90 find it necessary to provide the combination bridge wall and air box at the back. The air entering the back of the furnace through the box meets and consumes any possible smoke which may not have been consumed 95 by the action of the air and steam jets in the furnace.

What I claim as my invention is:

In a boiler the combination with a furnace provided with the usual front plate, entry door and grate bars, of a cross plate secured to the front end of the furnace beneath the front plate and door, said cross plate being supplied with a plurality of air inlet openings, tubes carried by the cross plate and continuous with the openings, said tubes entering the furnace beneath the grate, a steam pipe leading from the top of the boiler and passing lengthwise of the cross plate, steam nozzles secured at intervals to 105 the pipe and passing into the tubes aforesaid, a controlling valve in the feed pipe, an adjustable damper carried by the cross plate, a second steam feed pipe communicating with the boiler and passing to the front end 110 of the furnace, a steam nozzle entering the furnace at a point above the door, said nozzle communicating with the latter steam pipe and a valve in the said latter steam pipe, as and for the purpose specified. 115 120

Signed at Winnipeg this 14th day of October, 1913.

CHRISTIAN SCHNEIDER.
